J. A. Richards.

UNITED STATES PATENT OFFICE.

STEPHEN D. SHAMBARGER, OF NEW BRITAIN, CONNECTICUT, ASSIGNOR OF ONE-HALF TO HENRY NORTON, OF SAME PLACE.

WRENCH.

SPECIFICATION forming part of Letters Patent No. 441,199, dated November 25, 1890.

Application filed August 16, 1890. Serial No. 362,239. (No model.)

To all whom it may concern:

Be it known that I, STEPHEN D. SHAMBARGER, a citizen of the United States, residing at New Britain, in the county of Hartford and State of Connecticut, have invented certain new and useful Improvements in Wrenches, of which the following is a specification.

This invention relates to wrenches of the class having a movable frame and a sliding jaw movable independently of the frame, the object being to furnish a strong and convenient wrench, suitable for the purposes of machinists, cyclists, and others who require a quick-adjustment wrench arranged for taking firm hold of the screw or nut to be turned thereby.

In the drawings, accompanying and forming a part of this specification, Figure 1 is a side elevation, partially in section, of a wrench embodying my present improvement. Fig. 2 is a plan view of the under side of the wrench. Fig. 3 is a cross-sectional view in line *a a*, Fig. 1.

Similar characters designate like parts in all the figures.

The wrench consists, in a general way, of the wrench-bar B, having the head 3 formed thereon, and constituting the outer jaw of the wrench, the movable block or frame D, fitted to slide on said bar and carrying means for operating the movable wrench-jaw, and having, also, means for fixing it at predetermined points along on the wrench-bar, and a movable jaw, also fitted to slide on the wrench-bar and in the movable block and connected with said jaw-actuating devices. The wrench-bar is or may be furnished with the usual handle, as 4, whereby the instrument may be conveniently grasped by the user. The movable block is fitted throughout its length to inclose and slide on the wrench-bar, and has in the upper or back part thereof a lock-pin 5, whose point projects into the wrench-bar mortise and is fitted to engage with suitable holes, as 6, formed at regular distances apart in the upper edge of said bar. Said lock-pin is independent of the movable jaw-actuating devices, so that the movable frame may be set at any of the predetermined points along the wrench-bar by means of said lock-pin only. For operating the said lock-pin this

pin is formed with a screw-thread thereon and with a head for turning the same, the screw-thread being fitted to turn closely but freely in the internal thread or nut formed in the outer wall of the movable block itself, as indicated by the conventional shading in the sectional part of the drawings, Fig. 1.

The engagement between the wrench-bar and the lock-pin is made by inclined surfaces, 60 the holes 6 being of relatively large diameter and formed conical, and the lock-pin having a conical point whose angles correspond to those of said holes. By this means, when the lock-pin is screwed firmly against said conical surfaces and pressure is brought against the movable frame D, tending to slide back the same, said conical surfaces act as wedges to draw the movable frame more firmly against the inner side of the wrench-bar, and 70 by reason of the relatively fine pitch of the lock-pin thread sets said pin firmly in place, so that it is in effect "checked," as by a check-nut, when the wrench is in use, thereby securing safety against accidental unlocking 75 of the movable block and preventing any sudden opening of the jaws while using the wrench.

The movable frame consists of a frame fitted, as stated, to slide on the wrench-bar and 80 to receive the above-described lock-pin and constructed to receive the stem of the movable jaw and the devices for actuating the same. Said frame is bored parallel to the wrench-bar for receiving the stem 7 of the 85 movable jaw C. The bore 8 is enlarged throughout the greater part of the length thereof to receive the retracting-spring 9, which lies around the stem 7, as shown in the drawings, and reacts against the face 10 of 90 the inner end of the reduced part of said bore. At the rear end of the bar 7 a slot or mortise 14 is formed, in which is pivoted the end of the hand-lever 16, that is connected at 18 to the end of the stem 7 of the jaw C. The forward edge 30 of the arm 24 of the lever is rounded on a line, substantially as described, concentric to the pivot 18, so the pressure is directly against the face 31 of the slot 14, so as to relieve the pin, and also to secure increased bearing-surface. The movement of the lever is limited by the stop-face 20 and

the edge 22 of the working end or arm 24 of said lever, as indicated by the dotted lines in Fig. 1.

In using the wrench the operator grasps 5 the instrument by the handle 4 and loosening the lock-pin 5 sets the movable frame D at the point required to bring the distance between the jaw-faces slightly greater than the thickness of the nut or screw-head to be turned, 10 and then sets the lock-pin as hereinbefore described. Then placing the wrench over the nut or screw-head, the operator grasps the handle 16, and closing it forcibly toward the handle 4, throws forward the jaw C, as 15 indicated by dotted lines in Fig. 1, until the said head or nut to be turned is firmly gripped between the said jaw-faces. Having done this, the nut or screw is then readily turned in the ordinary manner without jamming the 20 corners thereof and without danger of the wrench slipping off, and thus injuring the operator. Having turned the piece sufficiently, the handle 16 is released, when the spring 9, 25 acting against the arm 24 of said lever, (said arm being connected to the sliding jaw,) retracts the sliding jaw C to its former position. It will be observed that the jaw C not only slides, as herein stated, but slides over the bar B, which is inclosed thereby, so that when 30 pressure comes between the jaw-faces, and thereby tends to throw the jaw C out of alignment in the manner common to all wrenches of the so-called "monkey-wrench" class, the said jaw is firmly resisted by the bar B extending through the same. This feature 35 relieves the stem 7 of lateral strain, whereby it may be made of a comparatively small size, as shown in the drawings, while retaining ample strength and rigidity for performing the 40 work required. This results in making feasible for the uses hereinbefore set forth a type of wrench not hitherto found practicable for such uses. The result is the construction of a neat and effective instrument of this class, 45 free of external springs and objectionable features, and which may be made by the interchangeable method of good workmanship and at a low cost.

It will be observed that the movable frame 50 D is perforated its entire length for the bar B, and also has another perforation its entire length for receiving the stem of the movable jaw C, there being a wall 2 between said perforations throughout the length of said frame, 55 against which wall said bar is forced by the action of the lock-pin, and also, as hereinbefore set forth, by the combined action of the lock-pin and the pressure on the lock-frame due to using the wrench for the turning of a 60 nut or screw.

One object of the stop-faces 20 and 22 is to hold the handle 16 at a convenient distance from the handle 4 when the handle 16 is fully closed, as indicated by dotted lines in Fig. 1, 65 and also to hold the jaw C in a substantially

fixed position on the wrench-bar when the wrench is to be used for turning irregularly-formed pieces—such, for instance, as the curved heads of thumb-screws and the like, which are used largely on bicycles, and which cannot, by reason of their shape, be grasped firmly after the manner of grasping ordinary nuts and screws. 70

Having thus described my invention, I 75 claim—

1. In a wrench, the combination, with the wrench-bar having the fixed jaw, and having the movable frame fitted to slide on said bar, of the movable jaw actuated independently of the frame by devices, substantially as described, carried on said frame, and the conically-pointed lock-pin screwed through the outer wall of said frame and engaging with correspondingly-conical recesses in the back edge of the wrench-bar, whereby on using the 80 wrench said frame is closed onto the forward edge of the bar and the lock-pin is checked against movement. 85

2. The combination, with the wrench-bar having the fixed jaw, of the movable frame fitting over said jaw and provided with means, substantially as described, for setting the frame at predetermined points along on the wrench-bar, said frame being bored parallel with the wrench-bar, substantially as described, for receiving the stem of a movable jaw and being constructed for carrying the jaw-actuating lever, the movable jaw fitted to inclose the wrench-bar and carried thereon and having a stem extending into said movable frame, and the jaw-actuating lever pivoted in the frame and connecting with said stem in said bore, whereby retraction of the jaw is resisted by its stem and deflection thereof by the wrench-bar. 90 95 100

3. In a wrench, the combination, substantially as described, with the wrench-bar and with the movable frame fitting over said bar and bored, substantially as set forth, to receive the stem of the movable jaw and to 110 carry the jaw-actuating lever, of the movable jaw fitted to slide on said bar and having the stem 7 sliding in said bore, the lever pivoted to the frame and connected to the end of said stem, and the spring carried in an 115 enlargement of the bore around said stem and acting against said lever for retracting the jaw. 120

4. In a wrench, the combination, substantially as described, with the wrench-bar, the 120 frame, and the spring-retracted movable jaw, of the hand-lever 16, connected with the jaw, substantially as shown, and limited in its movement in one direction by the jaw and in the other direction by the stop-surfaces 20 125 and 22.
